UNITED STATES PATENT OFFICE.

ELBERT MONROE TOLSTON, OF MACON, GEORGIA, ASSIGNOR OF ONE-HALF TO LEE LAIN, OF BIBB COUNTY, GEORGIA.

GRADE-CROSSING GUARD.

1,362,650.

Specification of Letters Patent. Patented Dec. 21, 1920.

Application filed April 6, 1918. Serial No. 227,049.

To all whom it may concern:

Be it known that I, ELBERT MONROE TOLSTON, a citizen of the United States, residing at Macon, in the county of Bibb and 5 State of Georgia, have invented certain new and useful Improvements in Grade-Crossing Guards, of which the following is a specification.

My invention relates to grade crossing 10 guards and more particularly to that type which is automatically opened and closed.

The object of my invention is to provide a crossing guard in which the guard or gate is closed by an electric motor, and 15 opened by a spring or by gravity.

Furthermore, the object of my invention is to produce a grade crossing guard having a danger signal suitably secured on the 20 guard having electrical connection whereby the danger signal may be visible at night as well as in the daytime.

Furthermore, the object of my invention is to produce a grade crossing guard which will normally stand open by means of a 25 spiral spring, and which will be closed by a motor having suitable connections with the guard and having a danger signal carried by the guard in which an intermittent light is secured.

30 Finally the object of my invention is to provide a grade crossing guard automatically operated in one direction by a motor which may be operated from the train, depot, signal tower or in yards by an operator using the ordinary push button for forming the contact by which the current is supplied to the motor or the contact may be formed by a contact brush carried by the engine or car and contacting with a supporting board upon which the wires are secured so that the current will be closed between the motor and the batteries supplying the same. The invention possessing advantages in points of simplicity and efficiency, 45 consisting in the details of construction and in the arrangement and combination of parts to be hereinafter more fully set forth and particularly pointed out in the claims.

In describing my invention in detail reference will be had to the accompanying drawings forming part of this specification, wherein like characters denote corresponding parts in the several views and in which:—

Figure 1 is a perspective view of my improved grade crossing guard,

Fig. 2, is a diagrammatic view illustrating the electrical wiring for operating the device,

Fig. 3 is a fragmentary view showing the 60 wiring for the modification,

Fig. 4 is an elevation of the guard or gate,

Fig. 5 is a side elevation partly in section of the guard,

Fig. 6 is a fragmentary sectional view of the contact brush carried by the train,

Fig. 7 is a fragmentary view of the danger signal for the guard, and

Fig. 8 is a fragmentary view of a front 70 elevation of the contact brush secured to the front beam of the engine.

In the drawings 1 indicates the track of a railroad or railway which may be either a single or double track system as my improved crossing guard may be operated upon both systems and will require only the duplication of the several parts comprising the invention and which is crossed by the roadway 2 at any angle. On each side of 80 the roadway 2 and parallel with the railroad track I secure posts 4 and 5. A gate or suitable guard 6 is secured by hinges to the post 5 and a spiral spring 7 having one end secured to the guard and its opposite end 85 secured to the post 5, normally holds the guard in an open position when it is closed, immediately after the train has passed beyond the roadway, the force of the spring will bring the gate to an open position. 90

A motor 8 having a winding drum 9 connected thereto is secured on the post 4 and a flexible connection 10 having one end secured to the outer end of the guard or gate is connected at its opposite end to the winding drum and when the drum is operated by the motor the flexible connection is wound thereon and by such movement of the flexible connection the gate is closed. The flexible connection is of a sufficient length so 100 as to permit the guard or gate being swung back to the position shown in dotted lines in Fig. 2.

I secure on the guard or gate, intermediate its length, a danger signal having a 105 rectangular shaped frame 11 and a bottom board or plate 12 on which I secure an electric bulb 13. A hood 14 provided with

transparent letter on each side fits over the frame thereby protecting the light and displaying a danger signal during the night when the position of the gate cannot be observed by the operator of any vehicle. At one end of the frame, a post 15 extends above the hood to which I secured the wires supplying the current to the lamp 13.

A contact brush has a head piece 16 in 10 which fine copper wire forming a brush 17 is secured and between the head piece 16 and the wire brush 17 I secure suitable insulating material 18 to prevent the current from passing through the brush head. A 15 spiral spring 19 having one end secured to the head piece 16 and its opposite end secured to the side of the engine cab, 20, or when my invention is used on an electric railway, the spring may be secured upon 20 the outside of the front car, it only being necessary to secure the brush in such position that it will contact with the wires on a supporting board 21 which will be hereinafter more fully described.

25 The electric operation of my improved grade crossing guard comprises two separate systems, one system to operate the gate or guard and the other to furnish current to the light 13 in the danger signal. In my 30 preferred form I use ordinary dry batteries, but any other suitable source of electricity may be employed it being understood that I do not limit the use of my invention to the use of dry batteries.

35 A battery 23 is secured on the post 4 and connected to the motor 8 by a connecting wire 24. A line wire 25 having one end secured to the battery extends across the roadway 2 to a crossarm 26 on the top of 40 the post 5 and from there to the supporting board 21 and along the edge of the board 21 to its outer end where the wire terminates. A return wire 27 is secured to the supporting board immediately below the wire 25 45 and extends along the board 21 thence to the crossarm 26 and from there to the motor 8 thus providing an open circuit for the operation of the motor.

The current for the light 13 of the danger 50 signal is supplied by a battery 28 secured on the post 5 to which I attach a wire 29 which is suitably connected to the supporting board below the wiring for the motor. The wire 29 does not follow on one side of 55 the board continuously but passes through apertures in the board and continues along the rear of the supporting board a short distance and then returns to the front of the board, this provides contacts of short length, 60 which are broken and then renewed, causing an intermittent flashing of the light 13, in the danger signal. A return wire 30 is arranged in the same manner as the wire 29 and has its end connected to the battery 28 65 thereby forming a normally open circuit.

In the use of my device, when it is desired to provide a guard upon both sides of the railroad the parts above described are duplicated and arranged on each side of the track.

70 In the modification shown in Fig. 3, the wire supporting board 21, is secured on the top of the ties adjacent to one end, and the contact brush is attached to the front beam of the engine or car so that it will sweep 75 over the supporting board and form a contact with the wires.

The arrangement of the wiring, if desired may be placed in conduits in the ground and the supporting board located at 80 any desired distance from the crossing guard, it being my purpose to provide a crossing guard having means to automatically open and close the guard which can be erected and maintained at a nominal cost. 85

The operation of my device is as follows: The guard being held in an open position by the spiral spring 7, the contact brush on an engine or train passing the supporting board sweeps over the wires and closes the 90 circuits to the motor and lamp. The movement of the motor operates the winding drum and the flexible connection is wound upon the drum drawing the guard to a closed position. When the contact brush 95 passes beyond the supporting board, the contacts are broken and the force of the spring being exerted upon the guard moves said guard to an open position and such movement unwinds the flexible connection 100 from the motor and the guard stands then at an open position.

It is believed that the construction and operation of my invention will be fully understood from the foregoing description, 105 it being noted that various changes may be made in the proportions and details of construction without departing from the scope of my invention.

Having fully described my invention, 110 what I claim as new and desire to secure by Letters Patent, is:—

1. In a grade crossing guard, a guard provided with an intermittently lighted danger signal, said guard being suitably pivoted to a post and adapted to swing across a roadway adjacent a railway crossing, a motor for moving said guard in one direction, and resilient means for imparting motion to said guard in the opposite direction, separate 115 electrical means for supplying current to said motor and danger light signal substantially as described.

2. In a grade crossing guard, a guard pivotally mounted on a post, a motor, a winding 120 drum connected to and operated by said motor, a flexible connection having one end connected to the winding drum and its opposite end secured to the outer end of said guard whereby the rotation of the winding 125 130

- drum will move the guard to a closed position, a danger signal provided with an intermittently operated light secured on said guard, a supporting board secured parallel with a railroad track, separate electrical conductors between said board and motor, and between said danger light and supporting board, means for moving said guard to an open position as and for the purpose set forth.
3. In a grade crossing guard, a post secured on each side of a roadway adjacent a railroad crossing, a guard provided with a danger signal having an intermittently operated light, said guard being pivotally secured on one of said posts, a motor, a winding drum adapted to be rotated by said motor, flexible connection between the winding drum and outer end of said guard, a spiral spring for moving said guard to an open position and normally holding said guard in said position, batteries secured on said posts, a wire supporting board suitably secured parallel with the railroad track, electrical conductors between said motor and batteries, and between said supporting board and motor, a contact brush carried by an engine cab and adapted to sweep over the wires on the supporting board whereby a current is completed between said motor and batteries, and between said danger light signal and batteries substantially as described.
- In testimony whereof I affix my signature in the presence of two witnesses.
- ELBERT MONROE TOLSTON.
